UNITED STATES PATENT OFFICE

1,960,685

BURNER

George S. Thompson and Walter G. Bagley,
Pueblo, Colo., assignors to The Colorado Fuel
and Iron Company, Denver, Colo.

Application October 26, 1931, Serial No. 571,182

6 Claims. (Cl. 110—104)

Our invention relates to burners, and particularly to burners adapted for use with pulverized coal. An important object of the invention is to provide means for cooling the burner by secondary 5 air.

Another feature of the invention is the provision of practical means for igniting the pulverized coal. An object is to provide electrical means for such ignition, without the use of oil, gas, or other 10 intermediary.

A further object is to provide means for keeping the spark terminals clean and cool, and to prevent the spark terminals from gumming up.

Still other objects reside in details of construction and in novel combinations and arrangements of parts, which will appear in the course of the following description. In the drawing, like reference characters designate similar parts in the several views.

20 Figure 1 is a longitudinal section through a burner embodying features of the present invention, together with associated elements.

Figure 2 is a section taken on the line 2—2 of Figure 1.

25 Figure 3 is a section taken on the line 3—3 of Figure 1.

Referring more in detail to the drawing, the reference character 7 designates fire brick forming a furnace wall. A metal shell 8 is fastened on 30 the outer surface of the fire brick. The fire brick provides a chamber 9 having cylindrical and tapering portions 10 and 11 respectively. The outlet opening of the tapering portion is indicated at 12.

The cylindrical portion 10 of the chamber is 35 closed by an asbestos plate 13. The plate 13 and shell 8 are fastened to the fire brick wall by bolts 14 and nuts 15. Nipples 16 and 17 extending through the asbestos plate are preferably used for a peep hole and a connection with a source of secondary 40 air respectively.

High voltage electrodes 18 and 19 (such as 12,000 45 volts) also pass through the asbestos plate. The electrodes are offset within the chamber 10, as shown at 20 and 21. The electrodes have tips 22 and 23 extending toward each other at the ends of leg members 24. The offsets and bent ends allow the electrodes to be separated a sufficient 50 distance that particles of coal cannot lodge between the same and short circuit the electric system. Since the bent ends 22 and 23, where the sparks are desired, are closest together, short circuiting is improbable. The electrodes used in the present invention are shown in our pending 55 application Serial No. 552,164.

Centrally disposed within the chamber 9 is a

nozzle 25 having an externally projecting, threaded end 26 for connecting with a feeder for mixed pulverized coal and air. The nozzle is internally grooved at 27 to provide a guideway for a sliding, flat shank 28 of a deflector member 29. A set 60 screw 30 on the nozzle engages said shank.

The nozzle has a bell-shaped end 31 that is cut off at one side, to provide a side opening 32, shown in Figures 1 and 3. Opposite this cut portion, the deflector carries a ridge or projection 33, shown 65 in section in Figure 1 and in plan (except the corners) in Figure 3. This projection deflects the mixed air and pulverized coal laterally from the passage 34 (extending through the nozzle 25), out through the side opening 32, toward the tips 70 22 and 23 of the electrodes to facilitate ignition of the coal.

The end of the deflector is recessed for the reception of refractory material 35. A small amount of ash 36 has a tendency to accumulate 75 on this material during operation, but this is not objectionable for it protects the deflector.

The operation of the foregoing is thought clear. Instead of having to rely on a burning bed of coals, which may go out when the feed is cut off, 80 as in the case of other mechanical coal feeders, and having to re-build the fire, with the present invention the fire is completely shut off when not needed, and started anew practically instantaneously when needed.

The chamber 9 provides an annular secondary air space around the nozzle. This secondary air supply cools the electrodes and nozzle, keeps the electrodes from gumming up, and blows the spark into the pulverized coal mixture.

The projection 33 and side opening 32 are important features in affording means for readily igniting the pulverized coal mixture. The secondary air also directs the coal mixture and the spark together into the furnace.

It is also to be understood that changes may be made in the details of construction and arrangements of the parts without departing from the spirit and scope of the invention.

What we claim and desire to secure by Letters 100 Patent is:

1. In a furnace, a nozzle for feeding fuel to the combustion space thereof, an air-supply chamber having an outlet adjacent the discharge end of the nozzle, to provide the air required for combustion of the fuel, the nozzle being cutaway at its said discharge end, to provide a side opening communicating with the chamber, electrodes having a spark gap in the chamber establishing a point of ignition opposite said opening, and a deflector 105 110

- within said nozzle effective to restrict the nozzle discharge, and having means within said nozzle and adjacent said opening to deflect fuel through the opening to the spark gap. 80
5. 2. In a furnace, a nozzle for feeding fuel to the combustion space thereof, an air-supply chamber having an outlet adjacent the discharge end of the nozzle, to provide the air required for combustion of the fuel, the nozzle being cutaway at its 10 said discharge end, to provide a side opening communicating with the chamber, electrodes having a spark gap in the chamber establishing a point of ignition opposite said opening, and a deflector directing the fuel through the discharge end of 15 the nozzle toward the outlet of the air chamber, and the deflector having a projection opposite the side opening of the nozzle to deflect fuel through the opening to the spark gap. 85
3. In a furnace, a nozzle for feeding fuel to the 20 combustion space thereof, an air-supply chamber having an outlet adjacent the discharge end of the nozzle, to provide the air required for combustion of the fuel, the nozzle being cutaway at its 25 said discharge end, to provide a side opening communicating with the chamber, electrodes having a spark gap in the chamber establishing a point of ignition opposite said opening, and a deflector within said nozzle effective to restrict the nozzle discharge, and having means within said nozzle 30 and adjacent said opening to deflect fuel through the opening to the spark gap, said nozzle having longitudinally extending internal grooves, and said deflector having a flat shank slidable in the 35 grooves, said shank being effective to transversely divide said nozzle into two passages for delivery of fuel. 90
4. In a furnace, a nozzle for feeding fuel to the combustion space thereof, an air-supply chamber having an outlet adjacent the discharge 40 end of the nozzle, to provide the air required for combustion of the fuel, the nozzle being cutaway at its said discharge end, to provide a side opening communicating with the chamber, electrodes 45
- having a spark gap in the chamber establishing a point of ignition opposite said opening, and a deflector within said nozzle effective to restrict the nozzle discharge and having means within said nozzle and adjacent said opening to deflect fuel through the opening to the spark gap, said deflector having a flat shank extending interiorly of the nozzle and engaging its sides to divide its interior into two passages for delivery of fuel to the furnace. 95
5. In a furnace, a nozzle for feeding fuel to the combustion space thereof, an air-supply chamber having an outlet adjacent the discharge end of the nozzle, to provide the air required for combustion of the fuel, the nozzle being cutaway at its 100 said discharge end, to provide a side opening communicating with the chamber, electrodes having a spark gap in the chamber establishing a point of ignition opposite said opening, and a deflector within said nozzle effective to restrict the nozzle discharge and having means within said nozzle and adjacent said opening to deflect fuel through the opening to the spark gap, said deflector having a flat shank extending interiorly of the nozzle and engaging its sides to divide its interior into two passages for delivery of fuel to the furnace, and means cooperating with said nozzle to secure the shank in selected positions. 105
6. The combination of a furnace wall providing a chamber having a restricted outlet, a conduit in the chamber for supplying a mixture of pulverized coal and air, the conduit being partially cut away at its periphery to provide a side opening adjacent said restricted outlet, a deflector in the 110 conduit having a projection adjacent said opening to direct a portion of the mixed coal and air through the side opening, and electrodes in the chamber having the spark gap opposite the side opening and adjacent the restricted outlet of said 115 chamber. 120
